CLAIM

The ornamental design for a pair of sandals, as shown and described.

DESCRIPTION

FIG. 1 is a perspective view of a right sandal of a pair of sandals, showing our design;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a bottom view thereof;

FIG. 8 is a perspective view of a left sandal of the pair of sandals;

FIG. 9 is a top view thereof;

FIG. 10 is a left side view thereof;

FIG. 11 is a right side view thereof;

FIG. 12 is a front view thereof;

FIG. 13 is a rear view thereof; and,

FIG. 14 is a bottom view thereof.

The broken lines in the Figures depict portions of the pair of sandals that form no part of the claimed design.

The word mark for 'Limitless' applied to surfaces of the pair of sandals is a registered trademark of I AM Apparel, LLC, and forms no part of the claimed design.

1 Claim, 10 Drawing Sheets
